UNITED STATES PATENT OFFICE.

JOHN SLOAN, OF JOHANNESBURG, TRANSVAAL, SOUTH AFRICA.

ROCK PACK, PILLAR, OR LIKE SUPPORT FOR USE IN MINE WORKINGS.

Application filed March 31, 1926, Serial No. 98,920, and in the Union of South Africa May 30, 1925.

This invention relates to the rock packs, pillars, or similar structures employed for supporting the hanging wall or roof in mine stopes or other like underground workings 5 of mines and similar places. The invention relates in particular to that kind of pillar or structure commonly known as a "pigsty" pack.

The object of the present invention is to 10 provide means whereby a pack or similar supporting structure of the kind hereinbefore referred to can be built or constructed, which will be more efficient than existing packs, and considerably less expensive to erect than packs constructed according to existing methods or designs, as the use of timber can be dispensed with or the quantity reduced to a minimum.

A pack, pillar or like structure according 20 to this invention may be of triangular, square, polygonal, circular, oval, or of any other suitable and preferred shape in cross-section, and of uniform cross-sectional area, or of any other suitable and preferred form.

In the construction of the rock pack, pillar 25 or like structure, I employ a flexible wire netting or the like, which expression is to be understood as including wire netting, screening, et cetera, in which the wires are 30 twisted, woven or otherwise interlaced, intertwined, interlocked, or tied to form a mesh or spaces between the wires or strands of the netting, et cetera; also the material commonly known as expanded metal, in which 35 sheet metal is cut and then expanded or drawn out to form openings or apertures between the strips formed by the cuts or slits; and also any similar construction or network made of hoop iron or strips of metal.

The netting, et cetera, may be of any desired 40 and suitable mesh or size of aperture or opening, and the wire or the like employed in its manufacture be of any suitable gauge or thickness. The netting, et cetera, 45 may be made of single wires throughout, or have several groups of wires, the wires of each group being arranged parallel, or twisted, or otherwise connected together, placed along the edges or/and intermediate the 50 edges, with or without strengthening or reinforcing wires, or groups of wires, arranged vertically, horizontally, diagonally or otherwise of the netting, et cetera.

The wire netting, et cetera, is made of such 55 dimensions or width and length as to enclose or surround, one or more times, the space

which is to be filled with the waste rock or other material in constructing the pack, pillar or like support. The wire netting, et cetera, cage or structure can be built up of 60 a number of widths of netting connected together along their adjacent edges or selvages by wiring, or by wire or other suitable fastenings.

If desired or found requisite, as for example in the case of large packs, et cetera, wire stays or ties may be provided extending across the space enclosed by the wire netting cage or structure, and be arranged to extend from side to side, and consist of 70 one or more parallel or twisted wires of suitable gauge attached in any convenient manner at their ends to the netting, et cetera; or alternatively, wire netting or the like may be used in place of or in addition to such internal stays.

The wire or wires used in the construction of the netting or the like will be of such gauge or thickness as to afford the requisite strength in the completed structure or cage, 80 and the size of the mesh will to some extent depend upon the size of the pieces of waste rock to be used as the packing.

If found desirable the wire structure or skeleton cage and packing material may be 85 additionally supported or bound by arranging on the footwall or floor of the enclosed area of the mine stope, et cetera, one or more pieces of the wire netting, et cetera, which will be carried up the side of the wire structure and continued under the hanging wall or roof of said enclosed space. If found necessary or considered desirable, the additional support or binding could be extended down the opposite side of the wire 90 structure and, if desired, continued on the foot wall for any suitable distance, the edges or overlapping portions on the footwall being appropriately connected or fastened together. This additional support would be 95 more particularly suitable for use in the construction of a pack in a steeply inclined stope, where the portion of same positioned at the lower side of the stope would serve to keep the packing material from falling 100 out of position and down the stope until the pressure of the superincumbent hanging wall tightened the pack and retained the packing material in position.

The wire netting or the like will preferably be made complete before constructing the cage, for facilitating its erection in posi-

tion in the mine working. It may be made in the form of a coil like ordinary wire netting, or it may be made in panels or rectangular pieces of suitable length and width 5 to erect square, rectangular, or other shaped packs, or be made in suitably curved sections to suit circular, oval, or similar packs.

For the purpose of erecting the wire netting or like cage or structure, three, four, or 10 any other desired or requisite number of uprights, posts, standards, or poles of timber or other material may be employed, arranged between and more or less at right angles to the hanging wall and foot wall, or roof and 15 floor of the stope, et cetera. These posts or uprights will preferably be of a length approximately equal to the height of the hanging wall, or the distance between the foot and hanging walls of the stope, et cetera, and 20 they will be of suitable diameter or thickness. The posts or uprights will be secured in position between the foot and hanging walls by suitable means, such as, for example, wedges or the like driven in between 25 the ends of the posts and the foot wall and/or hanging wall.

The uprights or posts may be arranged so that they lie either within or without the wire structure, at the corners of such structure or in any position intermediate the corners or around the structure. These poles or posts will serve as a guide or support in the erection of the cage or structure, the latter being suitably attached to said posts.

30 The wire netting, et cetera, will be attached to the standards or posts by any convenient means, such as, for example, flexible wire, nails or staples. The ends of the wire netting will be brought together and 35 connected also in any suitable and convenient manner as by twisting the wires or strands together or around each other.

In place of the wire netting or the like, one or more stout wires may be wound 45 around or attached to the outside or inside of each of the poles and be extended or carried between the poles, and be arranged in the form of a spiral or as separate windings or rings around or at the inside of the posts, 50 so as to enclose the space between the posts with a cage-like structure to hold and retain the packing in position between the foot and hanging walls. The spiral or separate windings or rings can be supported or maintained 55 at the requisite distance or distances apart by positioning at suitable distances apart around the spiral windings or rings distancing wires threaded or interlaced in the spiral windings or rings and twisted together, or 60 attached to the spiral windings or rings by flexible wires or other suitable means. A wire cage or structure consisting of the spiral or separate windings or rings with the distancing wires may also have incorporated in 65 it further diagonal or other wires twisted or

otherwise suitably secured to the main wires to form a mesh of any desired size.

In the accompanying drawings, which form part of this specification, I illustrate several practical embodiments of my invention:—In the drawings,

Fig. 1 is an isometric projection of one embodiment of the invention arranged in a level stope or similar mine working.

Fig. 2 is an isometric projection of another embodiment of the invention, and

Fig. 3 is an isometric projection of one form of the wire netting, et cetera, structure for additionally supporting the form of the invention shown in Fig. 1, when the latter is used in an inclined mine stope or, the like.

As illustrated in Fig. 1, in which a square or rectangular wire netting cage or structure is shown, adapted for the erection or building up of a similarly shaped pack, the numerals 1, 2, 3, 4, represent the four corner posts or uprights inside and between which the wire netting or like structure or cage is built. In this construction, the wire structure or cage includes the parallel longitudinal wires 5 and the transverse or cross wires 6, shown threaded or interlaced with the wires 5 in the manner common in the manufacture of some forms of wire netting. Twisted or otherwise attached around the wires 5, 6, are the thinner wires 7 which, with the wires 5, 6, form the mesh of the netting. Although in Fig. 1 I show a portion only of the wires 7 for the sake of clearness, it is to be understood that with this form or embodiment of the invention the whole structure would include the wires 7.

The longitudinal wires 5 and the transverse or cross wires 6 at the back and sides of the structure are shown broken away to make the figure more readily understood.

The top and bottom edges or selvedges 8 preferably consist, as shown, of two (or more) wires to stiffen and strengthen the said edges and, if desired, at one or more points intermediate the edges or selvedges 8 the netting may be stiffened and reinforced by a plurality of wires.

The cage or structure shown in this figure consists of two widths of wire netting, the inner overlapping or adjacent edges 9 being shown connected together by the ends of internal reinforcing cross wire stays or ties 10, of which three are shown arranged in each of two directions. 11 are cross wire stays or ties placed across the structure between the upper edges or selvedges 8 thereof and shown arranged in each of two directions. Obviously any desired number of the stays or ties 10, 11, may be provided and arranged in any suitable positions to support the sides of the wire netting structure in the erection of the structure and in the filling or packing of the same with the waste rock, et cetera.

The wire netting cage or structure is

shown placed within the four posts 1, 2, 3, 4, and attached thereto by means of wire fixings 12. The posts 1, 2, 3, 4, may be allowed to remain in position after the erection 5 of the wire netting structure, or they can be removed after the pack has been completed by packing the waste rock or like material inside said structure.

Referring to the embodiment of the invention illustrated in Fig. 2 the wire netting or like cage or structure is shown of cylindrical shape or substantially circular in cross-section. In this case the four posts 1, 2, 3, 4, may as shown be arranged in pairs at opposite sides of the structure and the wire netting or like material of which the structure is built is shown constructed in the same manner as in Fig. 1, and attached to the posts also in like manner.

20 In Fig. 3 the additional support and binding for the lower side of the structure in the case of a comparatively steeply inclined stope is illustrated. As previously explained, a portion 13 of the wire netting, et cetera, is laid on the footwall or floor of the stope, a portion 14 placed against the lower side of the main wire netting cage or structure—indicated in dotted lines—and a portion 15 carried immediately beneath the 25 hanging wall or roof. For the purpose of erecting this additional support two additional posts or uprights 16, 17, may be provided and the portion 14 wired to the posts, as indicated at 18. As in the case of the 30 posts 1, 2, 3, 4, the posts 16, 17, could be allowed to remain in position after the erection of the entire wire netting structure, or they could be removed after the pack has been completed.

40 Although several embodiments of the invention are shown in the drawings, it is to be understood that I do not limit myself thereto and that many other forms of the wire structure or cage could be devised which 45 would serve the purpose of the invention, i. e. to retain the waste rock or like fragmentary material in position in the form of a pack or pillar until said material was held in position by the weight or pressure put 50 upon it by the hanging wall.

In some cases, such as comparatively flat stope, or other places, the wire structure or cage could be erected in position without the use of the posts or uprights.

55 In erecting or building a pack or pillar with the aid of the invention it will probably be found most convenient first securely to erect the supporting standards, uprights, pillars or posts and then to place one width 60 of wire netting, et cetera, in position inside and between the posts and to secure the same thereto. The waste rock or filling material could then be placed in position in the space so enclosed to within a short distance of 65 the top of the wire netting and any cross

wire stays or ties arranged and secured in position. A further width of the wire netting would then be placed in position inside and between the upper portions of the posts and the bottom edges of said further width 70 be connected to the top edge of the first-mentioned width of wire netting and the top cross wire stays or ties arranged in position and secured. The second or top width could now be secured to the posts, leaving one side 75 or a portion of one side open to allow of the filling material being placed in position to complete the pack. The loose end of the top width could then be secured to the post, or if left of a sufficient length to overlap the 80 adjacent end of the top width, then also secured to said latter end. As previously explained, the posts can now be removed or allowed to remain, as may be preferred.

What I claim as my invention and desire 85 to protect by Letters Patent is:—

1. A support for use in mine workings, including a skeleton metal cage for holding filling material packed in said cage, so that the cage serves to maintain the filling material in position until it takes the pressure or weight of the hanging wall or roof of the working, as set forth.

2. A support for use in mine workings, including a wire cage for holding filling material packed in said cage, so that the cage serves to maintain the filling material in position until it takes the pressure or weight of the hanging wall or roof of the working, as set forth.

3. A support for use in mine workings, including a skeleton metal cage, for holding filling material packed in said cage, so that the cage serves to maintain the filling material in position until it takes the pressure or weight of the hanging wall or roof of the working, and supporting posts for said cage fixed in the mine working, as set forth.

4. A support for use in mine workings, including a skeleton metal cage, for holding filling material packed in said cage, so that the cage serves to maintain the filling material in position until it takes the pressure or weight of the hanging wall or roof of the working, and cross stays attached to the skeleton cage and extending across the space enclosed by it, as set forth.

5. A support for use in mine workings, including a wire cage of substantially uniform cross-sectional area, for holding filling material packed in said cage, so that the cage serves to maintain the filling material in position until it takes the pressure or weight of the hanging wall or roof of the working, supporting posts for said cage fixed in the mine working, and cross stays attached to the wire cage and extending across the space enclosed by it, as set forth.

6. A support for use in mine workings, including a wire netting cage of substantial-

ly uniform cross-sectional area, for holding filling material packed in said cage, so that the cage serves to maintain the filling material in position until it takes the pressure
5 or weight of the hanging wall or roof of the working, supporting posts for said cage fixed in the mine working, and cross stays attached to the wire netting cage and extending across the space enclosed by it, as set forth.

10 7. A support for use in mine workings, including a wire netting cage of substantially uniform cross-sectional area, for holding filling material packed in said cage, so that
15 the cage serves to maintain the filling material in position until it takes the pressure

or weight of the hanging wall or roof of the working, supporting posts for said cage fixed in the mine working, cross stays attached to the wire netting cage and extending across the space enclosed by it, and a skeleton metal binding structure comprising top and bottom members and a side member, the side member being placed down the side of the support, and the top and bottom members retained in position by the weight of the filling material and roof of the mine working respectively, as set forth. 20 25

In testimony whereof I have signed my name to this specification.

JOHN SLOAN.
